CAMERA HOUSING

Ronald Emmerling, New City, N.Y., assignor to Berkey Photo, Inc., Paramus, N.J.

Filed Dec. 15, 1972, Ser. No. 315,352

Term of patent 14 years

Int. Cl. D16—01

U.S. Cl. D61—1 B

FIG. 1

FIG. 2

FIG. 3

FIG. 4

FIG. 5

FIG. 6

FIG. 7

FIG. 1 is a rear elevational view of a camera housing showing my new design;

FIG. 2 is a top plan view thereof;

FIG. 3 is a front elevational view thereof, with the lens and viewfinder covers in a closed position;

FIG. 4 is a bottom plan view thereof;

FIG. 5 is a left side elevational view thereof;

FIG. 6 is a right side elevational view thereof; and

FIG. 7 is a front elevational view thereof, with the lens and viewfinder covers in an open position.

I claim:

The ornamental design for a camera housing, substantially as shown and described.
